UNITED STATES PATENT OFFICE.

EDWARD A. HAYNES, OF PORT HURON, MICHIGAN.

CABLE SLING, JAM AND TRIP HOOK.

Application filed December 30, 1924. Serial No. 758,854.

To all whom it may concern:

Be it known that I, EDWARD A. HAYNES, a citizen of the United States, residing at Port Huron, in the county of Saint Clair 5 and State of Michigan, have invented certain new and useful Improvements in Cable Slings, Jam and Trip Hooks; and I do hereby declare the following to be a full, clear, and exact description of the invention, such 10 as will enable others skilled in the art to which it appertains to make and use the same.

This invention relates particularly to improvements in cable slings, jam and trip cable devices and means for clamping a load or bundle, composed, for instance, of a number of logs of wood, and means for releasing the clamp or clevis when desired.

An object of this invention is to provide 20 means for maintaining the cable sling under tension around the bundle so that when the cable sling including the bundle of logs, in this instance, is released or dropped into the hold of a boat or otherwise, the bundle remains in firm, compact condition until it is 25 desired to unload at a destination, when the bundle or load is lifted by means of a derrick or otherwise, and the sling released from tension whereby the contents of the 30 load or bundle will drop to the ground or, for instance, into the water.

In the drawings:

Fig. 1 is a side elevation view of the cable sling including the clevis device, in operative relation.

Fig. 2 is a side elevation view showing certain parts in section, of the clevis, including the jam, trip device, and main body member.

Fig. 3 is a plan sectional view taken through 3-3 of Fig. 2.

Fig. 4 is an end sectional view taken through 4-4 of Fig. 2.

In these views like reference numerals 45 designate similar parts.

The numeral 1 represents the cable sling having a loop 2 at one end adapted to be readily attached to a derrick line or otherwise. The cable sling extends in slidable relation through an opening 5 in the jam portion 6, the said jam portion 6 being pivoted at 7 to a trip element 8 having an eye opening at 9 to carry the snap hook 10 of a trip line 11, the said trip element 8 also having

a locking projection as at 12 to catch or lock 55 when in operative position under a lug 13 positioned on the main body portion 14 of the clevis. The main body portion 14 is furthermore formed with a hooked section 15 at one end to receive the jam member 6 in 60 locked relation, while an inclined notch 16 is formed in the main body portion 14 to receive a spindle 17 carrying a guide roll 18, the said spindle 17 and guide roll 18 being adapted to slide in the notch or bearing 16 65 to adjust for different diameters of the cable sling 1. An opening 20 is located in one end of the main body member to receive the permanently fastened end 21 of the cable 70 sling 1.

In operation it is merely required to place the cable sling 1 in a loose condition or otherwise, around the load or bundle 19 to be handled, pull up on the loop 2 by means of a derrick or other lifting device, the lifting 75 action or strain causing the sling around the bundle to tighten until the bundle is in a close, compact mass; the clevis including the jam 6, trip device 8, and main body member 14 being in position as clearly 80 shown in Fig. 1, acts to firmly clamp the bundle so that when released at the loop 2 from the lifting apparatus and dropped into the hold of a boat or otherwise, the load or bundle retains its compactness, the cable 85 sling, obviously, being left around the bundle. When the destination is reached or when it is required to release the components of the load, the bundle is again attached to a lifting device by the loop 2, raised to the desired height, when the trip line 11 is pulled, thereby releasing the trip element 8 from locked relation with the main body member 14 of the clevis, causing the load to 90 fall apart, as in the common instance of logs being dropped into the water after being unloaded from a boat. On the release of the cable sling the main body portion 14 of the clevis will hang from the loop 21 of the cable sling, while the jam 6 will be held in 95 free sliding relation on the cable through the opening 5 in the jam, the said jam, trip element and trip line swinging together. The trip line, if desired, may be detached from the clevis by means of a snap hook 10. Obviously, the main body portion 14 of the 100 clevis is released at one end 15 from the cable sling through the slot 22 whenever the 105

trip line 11 is pulled and the jam allowed to fall out of hooked relation with the main body member at 15.

What I claim is:

- 5 1. A clevis adapted for a jam and trip cable hook, comprising a jam member, a trip device, and a main body member, the jam member being adapted to be held firmly in hooked relation with one end of the main body member.
- 10 2. A clevis adapted for a jam and trip cable hook, comprising a jam member, a trip device, and a main body member, the jam member being adapted to be held firmly in hooked relation with one end of the main body member by means of a trip device.
- 15 3. A clevis adapted for a jam and trip cable hook, comprising a jam member, a cable passing freely through the jam member, a trip device, and a main body member, the jam member being adapted to be held firmly in hooked relation with one end of the main body member by means of the trip device, and the said cable.
- 20 4. A clevis comprising a jam member, a trip device, and a main body member, the jam member at one end being adapted to engage in hooked relation with one end of the main body member, the trip device being adapted to pivot on the opposite end of

the jam member when it is desired to release the jam and trip from locked relation with the main body member.

5. The combination with a cable sling, of a clevis, comprising a jam member, a trip device including a trip line, and a main body member, the jam member at one end having an opening adapted to receive a free sliding portion of the cable sling, while one end of said cable sling is fastened to one

end of the main body portion, the said trip line being fastened to the trip device, is adapted, when pulled, to release the jam and trip device from the main body member, one end of the cable sling remaining attached to the body member, while the jam and trip device will swing free from the body member, the jam sliding freely on the cable sling.

6. A clevis comprising a jam member, a trip device, and a main body member, the said jam member being adapted to receive a cable freely slideable therein the cable being guided by a guide roll carried on a spindle rotating in bearings comprising elongated slots in the main body portions, the said slots allowing for adjustment to different diameters of cable.

In testimony whereof I affix my signature.

EDWARD A. HAYNES.
